UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

PRINTING-MACHINE.

No. 831,042.

Specification of Letters Patent.

Patented Sept. 18, 1906.

Application filed August 19, 1905. Serial No. 274,881.

To all whom it may concern.

Be it known that I, ALBERT B. DICK, a citizen of the United States, residing at Lake Forest, in the county of Lake and State of Illinois, have invented a certain new and useful Improvement in Printing-Machines, of which the following is a specification.

The object of the present invention is to provide a simple yet effective mechanism for printing from a form of type, such type being either of the character commonly employed in printing-presses or, if desired, of the character better adapted for setting up by unskilled hands and having a printing-face at one end and a display-face at the other. In carrying out the invention to this end I employ a suitable frame having a vertically-adjustable pressure-roller and means for throwing the same to operative and inoperative positions. Coacting with such frame is a carriage adapted to receive the chase in which the form of type has been set up, and intermediate of such form and the vertically-adjustable pressure-roller I employ an ink-ribbon carried, preferably, by a roll at each end of the carriage, suitable mechanism being combined therewith for moving said ribbon step by step at predetermined speed, so as to present a fresh surface thereof for successive printing movements of the carriage and the form of type supported therein.

The invention is illustrated in the accompanying drawings, in which—

Figure 1 is a side elevation of a printing-machine employing my invention. Fig. 2 is a central longitudinal section thereof. Fig. 3 is a plan view, certain portions being shown in section. Fig. 4 is a detail vertical section on the line 4-4, Fig. 3; and Figs. 5 and 6 are detail views illustrating portions of the ribbon supporting and operating mechanism.

Referring to the drawings, in which similar letters of reference denote corresponding parts, the frame of the machine comprises, generally speaking, two side plates A A', which may be provided with cross bars or braces a a'. Said plates are provided with vertical slots a², through which extend the ends of the shaft b of the pressure-roller B. The ends of said shaft are journaled in arms C C', each of which is pivoted at c to the outer face of one of the side plates of the frame, the distant end of each arm being downturned, as shown at c', and provided with the toe c².

D designates a shaft journaled in the side plates A A' and projecting therethrough, the ends of said shaft being provided with cams d, said shaft and cams being operated, by means of a suitable finger-piece d', to bring the cams d into coaction with the toes c² of the hinged arms C C' to thereby elevate and depress the pressure-roller B, throwing the same to operative or inoperative positions, as desired. Pivottally mounted at e upon the outer face of each of the hinged roller-carrying arms C C' is a lock E, the lower end whereof is provided with a finger e', adapted when said lock E is rocked upon its pivotal point (the pressure-roller B being depressed) to coact with the shaft D. Each of said locks E includes an upward extension e², projecting into the path of a stop formed upon the carriage, as presently explained. The lower arm e³ of each of said locks coacts with a guide-stop e⁴, limiting the movement of said lower arm e³. Coil-springs F F, the lower ends whereof are connected with the hinged roller-carrying arms C C' and the upper ends with adjusting-nuts f, serve to exert upward tension upon said arms and to move the pressure-roller B to operative position.

The carriage overlying the mechanism just described includes the side members G G' and the end members g g'. Adjacent to their lower edges the side members G G' are provided with guide-ribs g², coacting with rabbits or grooves g³ in the plates A A' of the frame. Each of said side members G G' is also provided with a rack g⁴, which coacts with a pinion g⁵, carried by the shaft b of the pressure-roller B, so that as the carriage is moved forward, the racks g⁴ and pinions g⁵ being in engagement, the pressure-roller will be driven. This, however, does not apply to the rearward movement of said carriage, since the pinions g⁵ will be thrown out of engagement with said racks, as hereinafter explained.

Supported by the carriage in any suitable manner is the chase in which the type are set up. This may be of any desired construction, and I have here shown, merely for the purpose of disclosure, a rectangular chase having the side members H H' and end members h h', a cover h² being hinged at h³ to the end member h. Extending between the side members H H' of the chase are lateral partitions which may coact with type having on

one side a shoulder to prevent their passing entirely through said partitions. Such type forming no part of the present invention are not illustrated in the drawings. The object 5 of the cover h^2 is to prevent the type after the same have been set up from being pushed upwardly during the printing operation.

I here remark that it is obvious that, if desired, the interior of the chase described may 10 be removable, so that a chase either of the construction alluded to or of another and different construction may be set within the same and securely fastened in such position. These and other details in connection with 15 the form of the type-supporting mechanism may be varied at will without departing from the spirit of the invention. The chase may be secured to the carriage in any suitable manner—as, for instance, by the latches h^4 .

20 At either end the carriage is provided with brackets (preferably adjustable) carrying rolls or spools on which the ribbon I may be wound. The brackets L at the rearward end of the carriage are provided each with the 25 upwardly-extending portion l and the angular downturned portion l' , the forward end of the latter having the beveled portion l'' , its outer face carrying the lock-operating boss l^3 , coacting with the upper end e^2 of the lock 30 E . The beveled portion l'' of each bracket L coacts with a sheave l^5 , carried by an ear l^6 on one of the hinged roller-carrying arms C C' , so as to depress said roller in advance of the coaction of the boss l^3 and the arm e^2 , 35 such coaction resulting in moving the locks E on their pivotal points e and throwing the fingers e' into engagement with the shaft D , thereby locking said pressure-roller in inoperative position at the conclusion of the forward (printing) movement of the type-carriage. Each of the brackets L is provided 40 with the set-screw l^4 , engaging with one or another of a series of threaded orifices l^7 in the side members G G' of the carriage.

45 Mounted upon the upwardly-extending portion l of one of the brackets L is a sleeve m , through which extends a stub-shaft m' , to the outer end whereof is keyed or otherwise secured a knurled nut m^2 . Keyed or otherwise secured to said sleeve m is a ratchet-wheel m^3 , with which coacts the upper end of a lever m^4 , pivoted upon said stub-shaft m' , its lower end projecting downwardly and adapted to coact with a stop-pin m^5 , carried 55 on the outer face of the frame-plate A . Inside the bracket L the sleeve m is provided with a clutch member m^6 , inwardly pressed by means of coil-spring m^7 , said clutch member being provided with a pin m^8 , coacting with a slot m^9 in said sleeve, and the inner face of said member being serrated in usual manner to coact with the clutch member m^{10} , keyed or otherwise secured on the stub-shaft m' . The inner face of the clutch member m^{10} is 60 provided with a pin m^{11} , adapted to coact

with an orifice in the head n of the ribbon-spool N . As will be seen, the forward movement of the carriage brings the lever m^4 and pin m^5 into coaction, thereby through the ratchet m^3 turning the sleeve m , and thereby 70 the clutch member m^{10} and the ribbon-spool N , carried by said clutch member. If desired, I may employ a pawl m^{12} , coacting with the ratchet m^3 , to preclude accidental (independent) movement of said ratchet. On the 75 other side the upwardly-extending portion l of the bracket L is provided with a bearing O , through which extends a stub-shaft o , having the collar o' adjacent to one end and the knurled operating-nut o^2 at the other. Between the collar o' and the bearing O the stub-shaft is provided with a coil-spring o^3 . Said stub-shaft o coacts with the other end n' of the ribbon-spool N .

The brackets P P' at the forward end of 80 the carriage may be similar in construction to the brackets L , save that no provision need be here located for driving the ribbon-spool. To this end one of the stub-shafts p may be provided with a collar similar to the collar o' and 85 a coil-spring similar to the coil-spring o^3 , permitting the ribbon-spool N' to be readily placed in position on the inward ends of said stub-shafts, the ribbon being fed from this spool to the spool N in the manner above described.

R designates a roll the ends whereof are journaled in the brackets P P' at the forward end of the carriage. r designates a similar roll, which may be conveniently journaled in 100 a recess formed in the end member h of the chase or type-supporting frame. The rolls r' and r^2 at the forward end of the carriage are similarly arranged, and all these rolls will be of a length somewhat greater than the width 105 of the ink-ribbon I . Initially the ribbon is wound upon the spool N' . It is then passed over the roll R , under the roll r , under the roll r^2 , over the roll r' , and then made fast to the spool N . This brings it directly under 110 the faces of the type set up in the chase or type-frame above described. At its rearward end the carriage may be provided with the operating-handle N^2 .

S designates a feed-board, here shown as 115 provided with adjustable side and end guides S' S^2 S^3 . If desired, the forward end of said feed-board may be provided with a hood s to protect the upper surface of the sheet pile laid on said board from the ink-ribbon I .

The drawings illustrate the position of the several parts midway of the printing operation. Starting at the beginning this operation is as follows: The carriage is first pressed 125 forward, whereupon the beveled surfaces l'' are brought into contact with the sheaves l^5 , depressing the pressure-roller B . Next the bosses l^3 are brought into contact with the upper arms e^2 of the locks E , thereby throw- 130

ing said locks to engaging position and securely holding the pressure-roller in its inoperative position. The uppermost sheet of the pile laid upon the feed-board S may then be pressed forward, so that its forward end shall overlie the said pressure-roller. If now the carriage be moved rearward, the beveled surfaces p' of the brackets at the forward end of the carriage will ride over the sheaves t , and a moment later the bosses p^2 , making contact with the upwardly-extending arms e^2 of the lock E, will throw said lock to inoperative position, thereby leaving the pressure-roller free to rise after said beveled surfaces p' have been moved out of contact with the sheaves t . If now the carriage be again moved rearwardly, the moment the beveled surfaces p' and the sheaves t are thrown out of coaction the pressure-roller will rise, thereby moving the sheet upward and into contact with the characters on the printing-surfaces of the type held in the chase supported by the carriage and said chase, said sheet, and said pressure-roller moved forward in unison, the impression being printed upon said sheet meanwhile. At the conclusion of the printing operation the sheet is passed forward by the pressure-roller and may be received in a suitable tray, (not shown,) if desired. This forward (printing) movement of the carriage also causes, through the coaction of the lever m^4 and pin m^5 , the feeding of the ribbon from the spool N' to the spool N , so that for each printing movement of the carriage a fresh surface of the ink-ribbon will be interposed between the type-faces and the impression-sheet.

Having now described my invention, what I claim as new therein, and desire to secure by Letters Patent, is as follows:

1. In a printing-machine, the combination with a movable carriage and type carried in a plane thereby, of an underlying pressure-roller movable to operative and inoperative positions, means controlled by said carriage for actuating said pressure-roller, and an ink-ribbon between said roller and the type supported by said carriage, substantially as set forth.
2. In a printing-machine, the combination with a movable carriage and type carried in a plane thereby, of an underlying pressure-roller moved to operative and inoperative positions by the movement of said carriage, an ink-ribbon between said roller and the type supported by said carriage, and means controlled by said carriage for moving said ink-ribbon, substantially as set forth.
3. In a printing-machine, the combination with a movable carriage and a type-form detachably carried in a plane thereby, of an underlying pressure-roller movable to operative and inoperative positions, means controlled by said carriage for actuating said

pressure-roller, and an ink-ribbon between 65 said roller and said type-form, substantially as set forth.

4. In a printing-machine, the combination with a plane type-form and an underlying pressure-roller, of means for simultaneously 70 and interdependently moving said type-form and said pressure-roller in coaction, and an ink-ribbon between said type-form and said pressure-roller, substantially as set forth.

5. In a printing-machine, the combination with a plane type-form and an underlying pressure-roller of means for simultaneously 75 and interdependently moving said type-form and said pressure-roller in coaction, an ink-ribbon between said type-form and said pressure-roller, and means for actuating said ink-ribbon, substantially as set forth.

6. In a printing-machine, the combination with a movable carriage and a detachable type-form and ribbon-spools carried thereby, 85 the ribbon passing from one of said spools to the other being adjacent to the printing-faces of said type, of an underlying pressure-roller, and means carried by said carriage for throwing said roller to operative and inoperative 90 positions, substantially as set forth.

7. In a printing-machine, the combination with a movable carriage and a detachable type-form and ribbon-spools carried thereby, 95 the ribbon passing from one of said spools to the other being adjacent to the printing-faces of said type, of an underlying pressure-roller, and means carried by said carriage for throwing said roller to operative and inoperative positions and for actuating said roller when 100 the same is in operative position, substantially as set forth.

8. In a printing-machine, the combination with a movable carriage and a plane type-form and ink-ribbon mechanism carried 105 thereby, said ribbon being in operative relation to the printing-faces of said type, of an underlying pressure-roller movable relatively to said type-form and inoperative in one position of said carriage and type-form and operative in another position of said carriage and type-form, substantially as set forth.

9. In a printing-machine, the combination with a movable carriage and a type-form and ribbon mechanism carried thereby, of a pressure-roller underlying said carriage and movable into and out of operative relation to the type-form carried thereby, and locking and releasing mechanism for said pressure-roller operated by said carriage, substantially as 115 set forth.

10. In a printing-machine, the combination with a carriage and a type-form and ribbon mechanism carried thereby, of an underlying pressure-roller movable to operative 125 and inoperative positions, and mechanism intermediate of said carriage and said roller for locking said roller, for releasing said roller,

and for moving said roller simultaneously with the movement of said carriage and type-form, substantially as set forth.

11. In a printing-machine, the combination with a movable carriage and a type-form and ribbon mechanism supported thereby, of an underlying pressure-roller and a feed-board adjacent thereto, and means carried by said carriage for depressing said pressure-
5 roller out of operative relation to the type-form supported by said carriage, for releasing said roller and bringing the same into operative relation to the type-form supported by said carriage, and for moving said pressure-
10 roller, after its release, simultaneously with the movement of said carriage and type-form, substantially as set forth.

12. In a printing-machine, the combination with a movable carriage and a type-form supported thereby, of an underlying pressure-roller movable under the control of said carriage to operative and inoperative relations to said type-form, ribbon mechanism including ribbon-spools and a ribbon passing
20 between the same in operative relation to said type-form, and means controlled by said carriage for moving said ribbon, substantially as set forth.

13. In a printing-machine, the combination with a movable carriage and means for detachably securing a type-form therein, of ribbon-spools supported upon said carriage, an ink-ribbon connected with said spools and fed from one to the other by the movement
30 of said carriage, said ribbon being in operative relation to the printing-face of the type in said form, an underlying pressure-roller movable to operative and inoperative positions, its movement being controlled by that
35 of said carriage, and means for guiding an impression-sheet between said roller and said ink-ribbon, substantially as set forth.

14. In a printing-machine, the combination with a carriage having a rack and a

type-form supported by said carriage, of ribbon mechanism also supported by said carriage adjacent to the printing-face of the type, an underlying pressure-roller movable to operative and inoperative relations to said type-form, and a pinion movable with said 50 roller and coacting with said rack, substantially as set forth.

15. The combination with a flat, movable type-carrier and type supported in a plane therein with their printing-faces downward, of an underlying pressure-roller movable relatively to said type and in correspondence with the movement of said carrier, said roller being adapted to support a sheet fed to the point of coaction of said roller and said type 60 and to permit said sheet to be simultaneously imprinted upon and passed bodily beyond such point of coaction, also in correspondence with the movement of said carrier, and an inking device for said type, substantially 65 as described.

16. The combination with a flat, movable type-carrier and type supported in a plane therein with their printing-faces downward, of an underlying pressure-roller movable relatively to said type and in correspondence with the movement of said carrier, said roller being adapted to support a sheet fed to the point of coaction of said roller and said type and to permit said sheet to be simultaneously 75 imprinted upon and passed bodily beyond such point of coaction, also in correspondence with the movement of said carrier, and an ink-ribbon between said pressure-roller and said type, said ribbon being movable simultaneously with the movement of said type, substantially as described.

This specification signed and witnessed at Chicago, Illinois, this 2d day of August, 1905.
